UNITED STATES PATENT OFFICE.

WILLIAM H. DE VANE, OF CAESAR, MISSISSIPPI.

TURPENTINE-GATHERER.

1,249,916.

Specification of Letters Patent. Patented Dec. 11, 1917.

Application filed May 25, 1917. Serial No. 170,913.

To all whom it may concern:

Be it known that I, WILLIAM H. DE VANE, a citizen of the United States, residing at Caesar, in the county of Hancock and State 5 of Mississippi, have invented certain new and useful Improvements in Turpentine-Gatherers; and I do hereby declare the following to be a full, clear, and exact description of the invention, such as will enable 10 others skilled in the art to which it appertains to make and use the same.

The invention relates to improvements in turpentine gatherers.

The object of the present invention is to 15 improve the construction of turpentine gatherers and to provide a simple, practical and efficient device of strong, durable and inexpensive construction adapted to be readily applied to and removed from trees without 20 injuring the same and without liability of leaving nails or other metallic fastening devices in the wood to come in contact with the saws of mills, and capable also of collecting and directing into a turpentine cup 25 all of the turpentine from the gash of a tree and thereby eliminate the waste incident to the use of turpentine gatherers of the construction ordinarily employed.

It is also an object of the invention to 30 provide a turpentine gatherer of this character which will enable a child to readily remove and replace the turpentine cup in the device so that experienced labor will not be required for removing the accumulated sap.

With these and other objects in view, the invention consists in the construction and novel combination of parts hereinafter fully described, illustrated in the accompanying 40 drawing and pointed out in the claims here-to appended; it being understood that various changes in the form, proportion, size and minor details of construction, within the scope of the claims, may be resorted to 45 without departing from the spirit or sacrificing any of the advantages of the invention.

In the drawing:

Figure 1 is a front elevation of a turpentine gatherer constructed in accordance with this invention.

Fig. 2 is a vertical sectional view of the same.

Fig. 3 is a perspective view of the hanger, 55 the apron and the turpentine cup being removed.

Like numerals of reference designate corresponding parts in the several figures of the drawing.

In the accompanying drawing, in which 60 is illustrated the preferred embodiment of the invention, the turpentine gatherer comprises in its construction a hanger constructed of a single piece of stout wire or other suitable material and consists of a lower 65 horizontal oblong cup-supporting loop 1, a vertical stem 2 rising from the loop at the center of the rear side thereof, and supporting arms 3 extending laterally in opposite directions from the upper end of the 70 stem and having terminal claws or prongs 4 adapted to be embedded in a tree, whereby the turpentine gatherer is secured to the same. The wire is preferably galvanized 75 malleable iron and the material is twisted to form the stem 2, and the supporting arms 3, which have a slight curvature or forward bowing to conform to the configuration of the trunk of a tree, are adapted to support a turpentine apron or chute 5 constructed 80 of galvanized sheet iron or other suitable material and brazed, riveted or otherwise secured to the supporting arms 3. The supporting arms 3 are provided with forwardly 85 projecting supporting loops 6 of approximate V-shape or U-shape and arranged at an inclination and adapted to extend beneath the apron, which has its upper edge 7 projecting above the arms preferably about one-half of an inch, but the distance 90 of course may be varied, and the upwardly projecting portion of the apron enables the latter to be introduced into a groove formed in the tree by a grooving tool or other instrument such as a hack so that the apron 95 will fit snugly and collect all of the turpentine or sap exuded from the gash of a tree and direct the turpentine into the turpentine cup. This will eliminate the loss which is incident to the employment of the turpentine gathering devices ordinarily in use 100 in lumbering districts.

To install the hanger, it is only necessary to brush off the rough bark with an ax or a number one sized hack or other suitable 105 tool, cut a groove under the bark straight across the tree and press the apron up under the groove and pull the claws as far as they will spread and drive them in, and the hanging of the device is effected. The 110 corners of the apron are turned or bent up, as shown, the upturned portion being spaced

from the upper edge of the apron, which has a slight curvature to conform to the configuration of a tree, and the spacing of the upturned corner portions from the upper edge will enable the said upper edge to be introduced into the groove of the tree without the corner portions interfering with the close fit of the apron to the tree.

The cup 8, which may be constructed of galvanized sheet metal or any other suitable material, is oblong in plan view and tapers downwardly at the end to fit within the loop or frame 1 and the cup may be readily removed from the loop or frame 1 by a child and experienced help will not be required to empty the turpentine cups. The device may be readily taken down with a claw hammer or other tool without injuring the tree or the device. Also it is only necessary to sink the groove cutter through the bark cutting a groove slanting upwardly and inwardly across the tree and the smaller the grooving iron the better will be the mounting of the device on the tree.

The turpentine cup is of a length to extend beneath the entire lower edge of the apron and the taper of the cup facilitates this arrangement besides seating the cup in the loop.

What is claimed is:

1. A turpentine gatherer including a lower outwardly projecting loop adapted to receive a turpentine cup and an upper attaching and supporting portion connected with and carrying the loop and provided with means for engaging a tree, said upper attaching and supporting portion being also provided with inclined supporting bends or

portions, and an inclined apron mounted on the said attaching and supporting portion and arranged over the inclined loops or bends.

2. A turpentine gatherer including a lower outwardly projecting loop adapted to receive a turpentine cup and an upper attaching and supporting portion connected with and carrying the loop and provided with means for engaging a tree, said upper attaching and supporting portion being also provided with inclined supporting bends or portions, an inclined apron mounted on the said attaching and supporting portion and arranged over the inclined loops or bends, the upper edge of the apron projecting beyond the attaching and supporting portion and adapted to enter a groove in a tree.

3. A turpentine gatherer including a hanger constructed of a single piece of material bent to form a rectangular cup-receiving loop and extended upwardly from the loop at the inner side thereof to provide a stem, the terminals of the material being extended in opposite directions from the stem to form supporting and attaching arms, said supporting arms having terminal prongs and provided between their ends with inclined supporting bends, and an apron secured to the said arms and arranged on the said bends.

In testimony whereof I affix my signature in presence of two witnesses.

WILLIAM H. DE VANE.
